[57] CLAIM

The ornamental design for a faceless watch system, as shown.

DESCRIPTION

FIG. 1 is a top plan view of the faceless watch system of the present invention;

FIG. 2 is a bottom plan view of the faceless watch system of FIG. 1;

FIG. 3 is a left side plan view of the faceless watch system of FIG. 1;

FIG. 4 is a right side plan view of the faceless watch system of FIG. 1;

FIG. 5 is a front plan view of the faceless watch system of FIG. 1; and,

FIG. 6 is a back plan view of the faceless watch system of FIG. 1.

The end portions of the band are shown broken-away in FIGS. 1-4 to indicate indeterminate length.
